UNITED STATES PATENT OFFICE.

LOUIS K. SCOTFORD, OF CHICAGO, ILLINOIS, ASSIGNOR TO CHENEY TALKING MACHINE COMPANY, A CORPORATION OF ILLINOIS.

WINDING MECHANISM FOR SPRING MOTORS.

Application filed April 17, 1915. Serial No. 22,076.

To all whom it may concern:

Be it known that I, LOUIS K. SCOTFORD, a citizen of the United States, residing at Chicago, in the county of Cook and State of Illinois, have invented certain new and useful Improvements in Winding Mechanism for Spring Motors, of which the following is a specification.

This invention relates to improvements in winding mechanisms for spring motors, and has for its object to provide, in combination with a talking machine spring motor or the like, mechanism to automatically wind such motor which mechanism will automatically discontinue its functioning while the talking machine is being operated and when the spring is sufficiently wound.

My invention further resides in the specific construction and arrangement described in the following specification and shown in the accompanying drawings, in which:

Fig. 1 is a side elevation of my invention located in the casing, a portion of the same being broken away for clearness;

Fig. 2 is a plan view of the mechanism;

Fig. 3 is a side elevation of the main winding gear and ratchet;

Fig. 4 is a section along the line 4—4 of Fig. 3;

Fig. 5 is a plan detail view of the intermediate gear and its mounting;

Fig. 6 is a similar view of the intermediate gear actuating pinion;

Fig. 7 is a bottom plan view of the brake; and

Fig. 8 is a section along the line 8—8 of Fig. 7.

Like numerals refer to like elements throughout the drawings, in which 10 indicates generally the casing of a talking machine having the top 11 through which projects the tone arm 12 carrying the reproducer 13 which carries the needle 14, these features not forming a part of my invention. When the machine is being used, the needle 14 rests upon the record 15 carried on disk 16. Extending downwardly through the top of casing 11 from the disk 15, and operatively attached to the latter, is a shaft 17 carrying a small gear 18 in mesh with and driven by a larger gear 19 which is carried upon a shaft 20, see Fig. 2. Secured to this shaft 20 is a small gear 21 meshing with the main actuating gear 22, see Fig. 1, which is carried by a spring barrel 23, forming with a second

spring barrel 24, the spring motor, of well known construction. Secured to the barrel 24 is a gear 25. This gear 25 meshes with a right angularly disposed driving pinion 26 carried on the shaft 27 which is journaled in brackets 28, see Figs. 1 and 2. Also mounted upon the shaft 27 is a gear 29 which meshes with an intermediate gear 30 which is carried on trunnion 30^c pivotally mounted between the arms of yoke 31.

The brackets 28 are integrally formed with and depend downwardly from the main plate A from which also extends downwardly the bracket 32, in which is provided an aperture 33 through which extends the rod 34, preferably formed integral with the yoke 31 and of reduced diameter to form a shoulder 31^a therewith, see Fig. 5. This rod 34 is slotted at 34^a and a pin 36 extends through the bracket 32 and slot 34^a, as shown in Fig. 5. This slot 34^a is of such size as to permit slight translation or sliding movement of yoke 31 and rod 34 relative to bracket 32, as will be apparent. Adjacent its end the rod 34 carries the nuts 34^b spaced from the bracket 32, and a spring 38 is coiled around the rod 34 between nuts 34^b and bracket 32. Meshing with the intermediate gear 30 is an actuating pinion 40, see Figs. 1 and 6, this pinion being mounted between the arms of the yoke 41 having a stub end 42 mounted in an aperture 32^b in bracket 32 by which it is secured by means of a pin 43. Below the actuating pinion 40 the bracket 32 is provided with the angularly disposed portion 32^c having a recess or cut-away portion 32^d therein, in which is mounted a worm 45 carried on sleeve 45^a, which is mounted on and attached to the rod 46, the latter being journaled in the portion 32^c of bracket 32. This worm 45 meshes with the pinion 40, as shown in Fig. 1 of the drawing. A shaft 46 is detachably secured by means of the collar or sleeve 48 to the armature shaft 49 of an electric motor 50 which is attached to a base 51, in turn secured on an angle bracket 52 attached to the wall of the casing 10.

Mounted upon the top wall 11 of the casing 10 is a braking mechanism 60 comprising a cap or casing 61, see Fig. 7 to the top 105 of which is pivotally attached the bell crank 62 having the engaging handle 62^a and the braking arm 62^b which latter is provided with a plug or insert 62^c of felt, leather, or the like, and adapted to contact with the 110

periphery of the disk 16 to bring the same to rest and maintain it at rest. Attached to the bell crank 62 in the cap or casing 61, is the arm 63 having the downwardly bent end 5 63^a to which is attached one end of the coiled spring 64 having its other end attached at 61^a to the interior of casing 61. This spring is so arranged, as is the bell crank 62, that as soon as the latter is started 10 from position out of contact with the disk 16, the spring will bring the plug 62 into contact with the latter and maintain it in such contact, as is well known in this art. The spring 64 is so located that it will not 15 draw the bell-crank out of inoperative position owing to the relative location of the crank and spring. That is, the lever 63 when moved to inoperative position carries the point of attachment of the spring 64 to 20 a point where the pull of the spring cannot move the bell-crank and brake to operative position. This construction is similar to that in common use. Secured to the underside of the top of casing 61 is a contact 25 61^b to which may be secured the terminal of one circuit wire 65. This contact 61^b is normally insulated by insulating washer 61^b from the casing 61, to the latter being attached the other wire 66 of the circuit, the 30 latter extending to a post or terminal 66^a on bracket 32. A second contact 68 is attached to and depends from the yoke 31, see Fig. 1, this contact 68 being normally in contact with the post 66^a. The contact 68 is normally insulated from the yoke 31 and is electrically attached to the wire 70 which leads 35 to one terminal 70^a of the motor 50. Attached to the other terminal thereof (not shown) is a second wire 71 leading to a 40 switch 67 which may connect it to a source of current 72 and from the switch extends a wire 73 connected to the casing 61.

It will be apparent, as shown in Figs. 7 and 8, that, with switch 67 closed, when the 45 brake bell crank 62 is in position braking or holding at rest the disk 16, contact will be established between the casing 61 and the contact 61^b, so that assuming switch 67 is in the correct position, the circuit will be completed and the motor 50 will be actuated to 50 wind the spring through the medium of worm 45 and the train of gears meshing therewith, the latter causing proper rotation, of gear 29. To prevent reverse rotation of the same I have rotatably mounted the gear 29 upon shaft 27 and adjacent such gear I have provided a ratchet wheel 90 attached by a pin 91, or the like to the shaft 27. A pawl 92 is pivoted to the gear 29, as 55 shown in Figs. 3 and 4, and is provided with an engaging end arranged to engage said ratchet 90 in one direction of rotation of the gear 29 to effect winding of the shaft 27 and the spring motor. A leaf spring 93, 60 which is attached to the gear 29, maintains

the pawl 92 in yielding engagement with the ratchet 90 so that in one direction of rotation of the gear 29, ratchet 90 will be rotated, while in the other direction it will be allowed to slip thereover.

It will be obvious that it is not desirable to continue the winding of the spring motor beyond a certain point, generally that at which it is substantially fully wound, and to overcome any such objection I have mounted 75 the intermediate gear 30, as described, and the action of the same is as follows:

As the gearing is operating to wind the spring motor, the gears all remain in the position shown in Fig. 1, intermediate gear 30 80 being retained in its proper position by means of the coil spring 38 which is of proper size and compression. When the spring motor reaches the point of sufficient winding, however, the further rotation of 85 the intermediate gear 30 will cause a yielding of the spring 38, the compression of the latter being less than that necessary to overcome the resistance of the spring motor and the intermediate gear 30 will partially roll on gear 29 against the action of spring 38 until such movement is prevented by pin 36 in slot 34^a. This slight rolling results in contact 68 being drawn out of contact with post 66^a so that the electric circuit is broken or 95 opened and further rotation of the motor 50 ceases.

It will thus be obvious that I have provided a mechanism for automatically winding a spring motor for talking machines, or 100 the like, which will only function when the rotatable disk or similar element is at rest, and will only wind the spring motor a desired amount, thereby eliminating danger of 105 breakage of the spring and other disadvantages which might ensue, were the safety means described above not provided.

It will also be apparent that my device is susceptible of numerous modifications and improvements, and I do not wish to be restricted to the form shown and described beyond the scope of the appended claims.

What I claim is:

1. In combination with a spring motor, a brake to control the actuation thereof, a 115 winding shaft for said motor, an electric winding motor, means operatively connecting said winding motor and said shaft comprising a train of gears, one of said gears being mounted for translation, an electric 120 circuit controllable by said brake arranged to supply current to said electric motor and a supplemental circuit breaker carried by said translatable gear and adapted to break said circuit when moved from normal position and to close the break in said circuit but not start said motor when moved into normal engagement.

2. In combination with a spring motor, a winding shaft therefor, a brake for con- 130

trolling the operation of said spring motor, an electric winding motor, means operatively connecting said winding motor and shaft, said means comprising a train of 5 gears, one of said gears being mounted for translation and arranged to move from normal position when said spring motor is sufficiently wound, an electric circuit controlled by said brake arranged to supply current to 10 said electric motor, and a pair of contacts in and forming part of said circuit, one of said supplemental contacts being mounted to move with said translatable gear whereby movement of the latter from normal position will open said circuit stopping the 15 electric winding motor, and the movement thereof into normal position not starting the motor.

3. In combination with a spring motor and an element arranged to be actuated thereby, 20 a winding shaft therefor, means for braking said element from actuation by said spring motor, a winding motor, operative connections between said winding motor and shaft, means operable by said braking means when 25 in braking engagement with said element to automatically actuate said winding motor, and when out of braking engagement to discontinue the actuation of said winding motor, and supplemental means interposed in 30 said operative connections to discontinue the actuations of said winding means when said spring motor is sufficiently wound.

In testimony whereof, I have subscribed my name.

LOUIS K. SCOTFORD.
